UNITED STATES PATENT OFFICE

115,511

DESIGN FOR A DOUGH MIXER

Harold Van Doren, Toledo, Ohio, assignor to Baker Perkins Company, Inc., Saginaw, Mich.,
a corporation of New York

Application April 7, 1939, Serial No. 84,128

Term of patent 14 years

To all whom it may concern:

Be it known that I, Harold Van Doren, a citizen of the United States, residing at Toledo, Lucas County, State of Ohio, have invented a new, original, and ornamental Design for a Dough Mixer, of which the following is a specification, reference being had to the accompanying drawing, forming a part thereof.

The figure is a front perspective view of a dough mixer, showing my new design.

The other side of the dough mixer is substantially like the side shown.

I claim:

The ornamental design for a dough mixer, as shown and described.

HAROLD VAN DOREN.
